(57) **CLAIM**

The ornamental design for an eyeglass retainer, as shown and described.

DESCRIPTION

FIG. 1 is a perspective view showing an eyeglass retainer in accordance with our new design;

FIG. 2 is a front view thereof, the rear view being the same;

FIG. 3 is a top view thereof;

FIG. 4 is an end view thereof;

FIG. 5 is a bottom view thereof;

FIG. 6 is a cross-sectional view along 6—6 of FIG. 5; and,

FIG. 7 is a front view with end beads shown in phantom. The elements shown in phantom are not part of the invention.
